UNITED STATES PATENT OFFICE.

JOHN H. DODGE, OF WORCESTER, MASSACHUSETTS, ASSIGNOR TO LOUIS C. SMITH, OF NEWTON, MASSACHUSETTS, AND HARRY R. SINCLAIR AND JOHN H. DODGE, BOTH OF WORCESTER, MASSACHUSETTS, TRUSTEES.

RATCHET-WRENCH.

1,177,764.

Specification of Letters Patent.

Patented Apr. 4, 1916.

Application filed March 17, 1915. Serial No. 14,991.

To all whom it may concern:

Be it known that I, JOHN H. DODGE, a citizen of the United States, residing at Worcester, county of Worcester, State of Massachusetts, have invented an Improvement in Ratchet-Wrenches, of which the following description, in connection with the accompanying drawing, is a specification, like characters on the drawing representing like parts.

This invention relates to ratchet wrenches of that type which can be converted into either a right-hand or a left-hand wrench, and the objects of the invention are to provide a novel wrench of this nature which is simple in construction and inexpensive to manufacture, in which the means for throwing either of the pawls into or out of operation extends longitudinally of the handle and is operable from the end thereof and is constructed so that the wrench can be changed from a right-hand to a left-hand wrench by a half turn of the operating means, and which has such a construction that said operating means will not be injured by a blow struck on the end of the handle, and which has other advantages all as will be more fully hereinafter described.

In order to give an understanding of my invention I have illustrated in the accompanying drawings a selected embodiment thereof which will now be described, after which the novel features will be pointed out in the appended claims.

Figure 1 is a view of the wrench with one of the cap plates removed to show the socket piece and pawls in plan view, said figure showing the pawls adjusted so that the wrench will operate as a right-hand ratchet wrench; Fig. 2 is a similar view showing the pawls adjusted so that the wrench will operate as a left-hand wrench; Fig. 3 is a section on the line 3-3, Fig. 1; Fig. 4 is a section on the line 4-4, Fig. 1.

The wrench comprises the usual body member 1 constructed with the handle portion 2 and the head or socket-receiving portion 3 in which the wrench socket 4 is rotatably mounted. This wrench socket is provided on its periphery with notches 5 which coöperate with the pawls 6 and 7

that are pivotally mounted in the body 1, each pawl being acted upon by a spring 8 which tends to move it into operative position. The pawls may be pivotally secured to the body member in any suitable way and as herein shown each pawl is provided at its end with a rounded head 9 which fits in a correspondingly-shaped socket 10, said head permitting the pawls to have the requisite rocking movement. The socket member 4 is of usual construction, and is confined in position by means of a removable cap plate 11 which, however, has been removed in Figs. 1 and 2. The parts thus far described are or may be such as are usually found in ratchet wrenches of this type and form no part of my present invention. In ratchet wrenches of this type it is customary to provide some controlling means by which either of the pawls 6 or 7 can be thrown out of operative engagement with the socket piece 4, depending on whether it is desired to turn the nut or other part to which the socket piece is applied in a right-hand or left-hand direction. It will be understood, of course, that if the pawl 6 is in operative engagement with the socket piece 4 and the pawl 7 is held in inoperative position, as shown in Fig. 1, a turning movement of the handle in the direction of the arrow *a* will turn the socket piece clockwise, Fig. 1, while if the position of the pawls is reversed with the pawl 7 in operative engagement with the socket piece and the pawl 6 in inoperative position, the socket piece 4 will be turned anti-clockwise by a movement of the handle in the direction of the arrow *b*, Fig. 1.

My present invention relates to the means for controlling the position of the pawls 6 and 7 and I have aimed to provide a simple construction for this purpose by which either pawl can be quickly thrown into or out of operative position and which is constructed so that it will not be injured by dropping the wrench on the floor or any ordinary abuse to which the wrench may be subjected. The controlling means for the pawls comprises a shaft 12 extending longitudinally of the handle portion 1, the

latter being made hollow for this purpose, and provided at its inner end with a projection 13, herein shown in the form of a pin, which is so constructed and situated that as the shaft 12 is turned in one direction or the other the pin will be brought into engagement with one or the other of the pawls, thus forcing the pawl backwardly against the action of its spring and 10 out of engagement with the socket piece 4. A half turn of the shaft 12 will, therefore, throw the projection from the position shown in Fig. 1 to that shown in Fig. 2. When the shaft is in its intermediate position with the projection 13 extending vertically, then both pawls are in operative engagement with the socket piece, as shown by dotted lines Fig. 2, and the socket piece is locked from movement in either direction.

20 The shaft 12 has at its outer end a head 14 provided with a knurled thumb-piece 15 by which it is turned, and this head is received in a socket 16 formed in the end of the handle 2, the head resting against a shoulder 17 at the inner end of the socket. This constitutes the bearing for the outer end of the shaft. The inner end of the shaft extends through an aperture in the portion 18 of the body member 1 and across a slot or passage- 30 way 19 in which the pin 13 operates, and into a socket 20 formed in the portion 21 of the body portion. This makes a firm bearing for the inner end of the shaft. The projection 13 is preferably removably secured 35 to the shaft, and this may conveniently be done by making it in the form of a pin which is screw-threaded into the shaft. The pin 13 thus not only operates as a means for throwing either pawl out of its operative position, but by its co-operation with the portion 18 of the body member, it provides means for holding the shaft 12 in operative position. The shaft can be removed when desired by simply unscrewing the pin 13.

40 The head 14 is fast to the shaft and because of the fact that it fits the socket 16 and engages the shoulder 17 any blow which may be received by the head 14 will be transmitted directly to the handle 2, thus preventing any 45 injury to the projection 13. If, therefore, the wrench should be accidentally dropped on the floor and should strike on the knurled head 14 no injury can be done to the pawl-operating means. This is an important ad- 50 vantage because wrenches of this nature are often carelessly handled. I have also pro- vided means for yieldingly holding the shaft 12 in its different adjusted positions. This is herein accomplished by making the 55 shaft with the three flat faces 22, 23 and 24, and providing a flat spring member 25 which is adapted to engage said flat faces. This spring member 25 is shown as supported at its ends on seats 26 formed in the body mem-

ber 1, the central portion of the spring being unsupported so that it can yield as the shaft 12 is turned. The spring 25 is held from movement longitudinally of the shaft by having the ends thereof received in notches 27 formed in the sides of the body member 1. When the shaft 12 is turned the corner between two adjacent flat sides will flex the spring 25 and the resiliency of the latter will hold the shaft in either of its three positions.

75 The wrench is very simple in its construction and is easily manufactured and assembled. It has the further advantage that it can be changed from a right to a left hand instrument by simply giving the shaft 12 a half turn, and it has the further advantage that the pin or projection 13 by which the pawls are operated cannot be injured or bent by dropping the implement or by any blow which may be delivered against the end of the handle.

80 While I have illustrated herein a selected embodiment of my invention, I do not wish to be limited to the constructional features shown.

90 I claim:

1. In a ratchet wrench, the combination with a body member having a handle portion and a socket-receiving portion, of a socket piece rotatably mounted in the socket-receiving portion, two oppositely-disposed pawls co-operating with said socket piece, a shaft extending longitudinally of the handle, and a projection rigid with and extending laterally from said shaft and adapted to be brought into direct engagement with either pawl by turning movement of the shaft, said projection also engaging the frame to retain the shaft in position.

105 2. In a ratchet wrench, the combination with a body member having a handle portion and a socket-receiving portion, of a socket piece rotatably mounted in the socket-receiving portion, two oppositely-disposed spring-pressed pawls, a shaft extending longitudinally of the handle portion, the latter being provided with a shouldered socket at its end, a head fixedly secured to the shaft and received in said socket, and a projection rigid with and extending laterally from said shaft and adapted to engage directly one or the other of the pawls as the shaft is turned, said projection also engaging the frame to retain the shaft in position.

110 3. In a ratchet wrench, the combination with a body member having a handle portion and a socket-receiving portion, of a socket piece rotatably mounted in the socket-receiving portion, two oppositely-disposed pawls co-operating with said socket piece, a shaft extending longitudinally of the handle, a projection extending laterally from said shaft and adapted to be brought into en-

gagement with either pawl by turning movement of the shaft, said shaft having flattened faces, and a spring sustained by the body member and coöperating with said flattened faces to hold yieldingly said shaft in adjusted position.

In testimony whereof I have signed my

name to this specification, in the presence of two subscribing witnesses.

JOHN H. DODGE.
